UNITED STATES PATENT OFFICE

168,877

SPOON OR SIMILAR ARTICLE

Grosvenor N. Allen, Oneida, N. Y., and Mary Parker Fleming, Newark, N. J., assignors to Oneida Ltd., Oneida, N. Y., a corporation of New York

Application May 1, 1952, Serial No. 19,556

Term of patent 14 years

(Cl. D54—12)

To all whom it may concern:

Be it known that we, Grosvenor N. Allen and Mary Parker Fleming, citizens of the United States, residing at Oneida, county of Madison, and State of New York, and at Newark, county of Essex, and State of New Jersey, respectively, have invented a new, original, and ornamental Design for a Spoon or Similar Article, of which the following is a specification, reference being had to the accompanying drawing, forming a part thereof, in which:

Figure 1 is a front elevational view of a spoon, showing our new design, with the conventional bowl element illustrated in broken lines;

Figure 2 is a back view of the spoon; and

Figures 3, 4, 5 and 6 are sections taken on the respective lines 3—3; 4—4; 5—5 and 6—6 of Figure 1.

We claim:

The ornamental design for a spoon or similar article, substantially as shown and described.

GROSVENOR N. ALLEN.

MARY P. FLEMING.
